UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR A WAFFLE-IRON.

59,496.

Specification for Design.

Patented Oct. 25, 1921.

Application filed June 6, 1921. Serial No. 475,460. Term of patent 14 years.

To all whom it may concern:

Be it known that I, JOSEPH F. LAMB, a citizen of the United States, and a resident of New Britain, in the county of Hartford, State of Connecticut, have invented a new, original, and ornamental Design for Waffle-Irons, of which the following is a specification, reference being had to the accompanying drawing, forming part hereof.

In the accompanying drawing:—

Figure 1 is a perspective view of the waffle iron showing my new design, and

Fig. 2 is an end view thereof with the hinged member slightly raised.

I claim:—

The ornamental design for a waffle iron as shown.

JOSEPH F. LAMB.
